UNITED STATES PATENT OFFICE

162,841

LEVEL AND PLUMB ATTACHMENT FOR
CARPENTERS' SQUARESTheodore T. King, Pampa, Tex., assignor of fifty
per cent to Corydon Winfield Hill, Pampa, Tex.

Application December 12, 1950, Serial No. 13,390

Term of patent 14 years

(Cl. D52—1)

To all whom it may concern:

Be it known that I, Theodore T. King, a citizen of the United States, residing at Pampa, in the county of Gray and State of Texas, have invented a new, original, and ornamental Design for Level and Plumb Attachment for Carpenters' Squares, of which the following is a specification, reference being had to the accompanying drawing, forming a part hereof.

Fig. 1 is a view in side elevation of a level and plumb attachment for carpenters' squares embodying my new design, with said attachment shown in one position on a conventional carpenter's square represented in broken lines;

Figure 2 is a view in top plan, and also showing the carpenter's square in broken lines;

Figure 3 is a view of the attachment in elevation as seen from the opposite side from that shown in Figure 1; and

Figure 4 is a view of the attachment in end elevation.

The broken line portions in the drawing are shown for illustrative purposes only.

I claim:

The ornamental design for a level and plumb attachment for carpenters' squares, as shown and described.

THEODORE T. KING.
